UNITED STATES PATENT OFFICE

GEORGES SELLIER, OF PARK RIDGE, NEW JERSEY, ASSIGNOR TO B. SAUBIAC & SON, INC., OF NEW YORK, N. Y., A CORPORATION OF NEW YORK

DESIGN FOR A BEDSPREAD

Application filed August 4, 1931. Serial No. 40,780. Term of patent 3½ years.

To all whom it may concern:

Be it known that I, GEORGES SELLIER, a citizen of United States, residing at Park Ridge, New Jersey, have invented a new, original and ornamental Design for Bedspread, of which the following is a specification, reference being had to the accompanying drawing forming a part thereof.

The drawing shows a plan view of a bedspread showing my new and ornamental design.

I claim:

The ornamental design for a bedspread substantially as shown.

GEORGES SELLIER.
